UNITED STATES PATENT OFFICE

128,645

DESIGN FOR A SPOON OR SIMILAR ARTICLE

Jay J. Sindler, Boston, Mass., assignor to Spir-It, Inc., Malden, Mass., a corporation of Massachusetts

Application April 29, 1941, Serial No. 109,692

Term of patent 14 years

To all whom it may concern:

Be it known that I, Jay J. Sindler, a citizen of the United States of America, residing at Boston, in the county of Suffolk and Commonwealth of Massachusetts, have invented a new, original, and ornamental Design for a Spoon or Similar Article, of which the following is a specification, reference being had to the accompanying drawing, forming a part thereof.

Fig. 1 is a front elevational view of a spoon embodying my new design; and

Fig. 2 is a section on the line 2—2 of Fig. 1.

Fig. 3 is a side elevational view of a spoon embodying the design.

I claim:

The ornamental design for a spoon or similar article, substantially as shown.

JAY J. SINDLER.
